UNITED STATES PATENT OFFICE

KARL F. WILD, OF PEORIA, ILLINOIS

SAFETY CATCH FOR PINS

Application filed October 24, 1933. Serial No. 314,814.

This invention pertains to safety catches for bar-pins and the like in the class of jewelry.

The objects of the invention are to provide a simple and efficient safety catch for pins, and to furnish a branched footing or base for the said catch by which to firmly attach it to the body of the pin for guarding against said catch being bent from its proper pin receiving position.

Besides these objects the device has various advantages in construction to be pointed out herein and to form the subject of certain of the claims.

As an aid to the full understanding of my invention the appended drawing is provided wherein—

Figures 1 and 2 are elevations of the catch of my invention shown attached to the pin-body which is illustrated in transverse section.

Figure 3 is a side elevation of a pin showing the catch of my invention and a branched footing or base therefor.

Figure 4 is a plan of a pin-body and a portion of the catch in horizontal section taken on line 4—4, Figure 3.

Figure 5 shows the catch and its base in perspective as created ready for attachment to a pin.

Figure 6 is a sectional elevation of part of the catch.

Figure 7 is a section of the catch on line 7—7 of Figure 6.

Figure 8 is a transverse section of parts of the catch showing the attachment of an actuating stud to a movable part thereof, and Figure 9 shows the underside of the actuating stud in one of its forms as seen from its end.

The catch includes a body-portion best shown in Figure 5 designated as a whole by the reference character 1, being created from a single piece of metal having a cylindrically curved head 2 formed into an open loop, the base of the body terminating in a series of four branched legs 3, in this instance for attachment to a support such as a bar-pin or the like designated at 4 in the first four figures. The extremities of said legs are pref-

erably inserted in holes 5 in the bar 4 and suitably held therein as by hard soldering or like method making an extremely rigid connection.

I have found that where a catch of this or any other type consists of a single upright member or post that the strains imposed thereon results in the catch being bent from its proper position out of line with the pin it is designed to receive. However, by employing the plurality of legs 3 spread in substantially the manner shown a thoroughly rigid job is the result and the catch cannot be altered in position.

While I prefer to seat the leg extremities in the bar 4 as described and illustrated I do not wish to be understood and confining myself to this particular method since other ways of anchoring may prove efficient; the plurality of spread legs being the important feature.

The inner surface of the cylindrically curved head 2 is a smooth unbroken one except for a slit 6 cutting through the said head in a plane at right angles to the axis of the bore of said head. An open ring 7, also cylindrically curved, and having a smooth and unbroken outer surface lies within the head 2 in a smooth turning fit, there being sufficient friction between the contacting surfaces to hold said ring 7 in any adjusted position as will be understood.

In order to impart rotary movement to the ring whereby to register its opening with that of the head 2 and in order, also, to prevent endwise movement of said ring a stud is provided which includes a head 8, Figure 8, having a stem which extends through the slot 6 of the head, said stem terminating in a reduced portion 10 which may be provided with screw threads to engage in a threaded hole 11 of said ring. Or, said portion 10 may be soldered, riveted, or otherwise fixed in the ring without resorting to screw threads.

It is preferable to provide a slight shoulder at 12 to abut upon the ring 7 whereby to space the head 8 slightly from the outer surface of the head 2 to prevent friction between these parts, or to permit free action.

If the portion 10 is screwed into the ring 7 the stem 9 may be round but if said portion is soldered or riveted in said ring the stem may be flattened at opposite sides as in Figure 12 at 13, this, however, being mere choice.

5 Since the ring and the bore of the head are substantially of the same diameter throughout the former may be slipped endwise into the latter and maintained in operating position by the named stud or stem 9 without further holding means.

I claim:

1. A safety catch including a body for attachment at one end to a support and having an open head at its other end provided with a bore, said head also having a slot partially severing it lying in a plane at right angles to the axis of the bore, a cylindrically curved open ring fitting the bore adapted to be inserted endwise into the said bore from one side of said head, and a stud adapted to be inserted through the slot to meet the ring and secured thereto, said stud adapted for rotating the ring and for retaining the same within said bore.

2. A safety catch including a body for attachment to a support and having an open head provided with a bore of a single diameter throughout its width, said head having a slot partially severing it lying in a plane at right angles to the axis of the bore, an open ring cylindrically curved substantially fitting the bore of the head, its exterior surface having the same diameter throughout its entire width, said ring adapted to be inserted into said bore from one side of said head, and a stud adapted to be inserted through the said slot and secured in said ring and projecting outward from said head.

3. A safety catch including a body for attachment to a support and having an open head provided with a bore of a single diameter throughout its width, and also having a slot partially severing it lying in a plane at right angles to the axis of the bore, an open ring substantially fitting the bore of the head, its exterior surface having the same diameter throughout, and said ring adapted to be inserted endwise into said bore, and a stud adapted to be inserted through said slot and secured in the said ring and projecting outward from said head, said stud having a shoulder abutting on the ring.

4. A safety catch including a head provided with a bore of a single diameter throughout its width, and having a slot therein in a plane at right angles to the axis of the bore, an open ring substantially fitting the bore, its external surface having the same diameter throughout, said ring adapted to be inserted endwise into said bore, a stud secured in the ring at a point opposite the slot of the head and having a shoulder abutting upon the ring and also having a head

terminating its outer end overlying a part of the head at said slot.

5. A safety catch for a bar pin for attachment to a support, the same having an open head provided with a bore, and also having a slot partially severing it lying in a plane at right angles to the axis of the bore, an open ring substantially fitting the bore adapted to be inserted endwise into said bore and rotatable therein, said head and ring being completely formed prior to their being assembled, there being a hole in the ring in register with the slot of the head when the parts are assembled, and a stud extending through the slot into the hole and secured in the latter.

6. A safety catch for a bar pin for attachment to a support, the same having an open head provided with a bore, and also having a slot partially severing it lying in a plane at right angles to the axis of the bore, an open ring substantially fitting the bore adapted to be inserted endwise into said bore and rotatable therein, said head and ring being complete in form prior to their being assembled, there being a threaded hole in the ring in register with the slot of the head when the parts are assembled, and a stud extending through the slot and threaded to engage the threaded hole.

7. A safety catch for pins including in its construction a support, a body having a plurality of extensions spaced from each other and at their extremities extending through the said support and secured therein.

8. A safety catch including a support, a body having at one end a cylindrically curved head and a cylindrically curved inner surface of substantially the same diameter throughout, said head being provided with a slot lying in a plane at right angles to the axis about which the head is curved, said body having a base terminating in a plurality of extensions spaced from each other, said support having holes therein, and said extensions lying in said holes and secured therein.

9. A safety catch including a support, a body having at one end a head provided with a cylindrical curved inner surface substantially of the same diameter throughout, said head being provided with a slot lying in a plane at right angles to the axis about which the said inner surface is formed, said body having a base terminating in a plurality of divergent spaced extensions, the support having spaced holes therein to register with and receive the extensions, the latter being secured in said holes, a cylindrically curved open ring lying within the head adapted for rotation therein, and a stud adapted to be inserted through the slot of the head and secured in said ring.

In testimony whereof I affix my signature.

KARL F. WILD.
